UNITED STATES PATENT OFFICE.

MICHAEL P. SHEA, OF GOLDFIELD, NEVADA.

REFRIGERATOR.

No. 906,313.

Specification of Letters Patent.

Patented Dec. 8, 1908.

Application filed July 16, 1907. Serial No. 384,081.

To all whom it may concern:

Be it known that I, MICHAEL P. SHEA, a citizen of the United States, residing at Goldfield, in the county of Esmeralda and State of Nevada, have invented new and useful Improvements in Refrigerators, of which the following is a specification.

This invention relates to an improved refrigerating device adapted to keep and preserve meat, butter, milk, vegetables and other food from spoiling without the use of ice; and it has for its object to simplify and improve the construction and operation of this class of devices.

With these and other ends in view which will readily appear as the nature of the invention is better understood, the said invention comprises a vertically movable box or receptacle arranged in a cavity in the ground where it will be kept beyond the direct influence of the sun, and at a comparatively low temperature.

The invention further includes a box or casing of simple and improved construction, arranged above and adjacent to the cavity in the ground, and containing simple hoisting mechanism whereby the receptacle may be elevated so as to render the contents thereof readily accessible through a door in said box or casing.

The invention further consists in the novel and improved construction, arrangement and combination of parts which will be hereinafter fully described and particularly pointed out in the claims.

In the accompanying drawing has been illustrated a simple and preferred form of the invention; it being, however, understood that no limitation is necessarily made to the precise structural details therein exhibited, but that changes, alterations and modifications within the scope of the invention may be resorted to when desired.

In the drawings, Figure 1 is a front elevation of a device constructed in accordance with the invention, showing the receptacle arranged in a cavity in the ground. Fig. 2 is a vertical sectional view, showing the receptacle elevated within the casing. Fig. 3 is a horizontal sectional view taken on the plane indicated by the line 3—3 in Fig. 1.

Corresponding parts in the several figures are denoted by like characters of reference.

The casing A of the improved device is composed of outer walls 1—1 and inner walls 2—2 which are properly spaced apart

to form an intermediate air space 3 which is rendered impervious or partially impervious to air and moisture by a non-conducting lining 4 of asbestos, or other suitable material which is preferably in the form of sheets secured exteriorly upon the inner walls 2—2. The walls of the casing are mounted upon a base 5; and the inner and outer walls, 1—1, 2—2, respectively, support the cap pieces 6 and 7 which are spaced apart so as to form an air space 8 communicating with the air space between the walls; this construction being readily effected by extending the outer walls upwardly above the inner walls. The casing A is supported by means of the base 5 above and adjacent to a cavity 9 in the ground; said cavity being of a cross sectional area as nearly as possible equal to that of the casing A.

The base 5 is provided with apertures 10 communicating with the air space 3 between the walls 1—1 and 2—2; and the outer cap 7 of the casing is provided with a vent tube 11 through which circulation of air may be maintained.

The casing A is provided with a pair of interior, oppositely disposed vertical guide rails 12—12 extending upwardly to the top of the casing and downwardly, through the base 5 into the cavity 9; said guide rails being extended to the bottom of the cavity where their lower ends are secured in any suitable manner; the base 5 is provided with a large opening or aperture 13 for the passage of the guide rails and also for the passage of a dumb waiter or receptacle 14 which is mounted for travel upon the guide rails, and provided with laterally extending guides or guards 15 engaging the rails. The receptacle constituting a dumb waiter is provided with suitable shelves 16 rendering it convenient for the purposes for which it is intended; said shelves being conveniently accessible through a door 17 upon the front part of the casing. Supported for rotation in the upper part of the casing is a shaft 18 carrying a drum or windlass 19 whereupon is wound a flexible element such as a rope 20, one end of which is made fast to the dumb waiter or receptacle 14 which may thus be raised or lowered; the drum carrying shaft being provided with an operating hand lever or crank 21 and with a ratchet wheel 22 engaged by a pawl 23 whereby reverse rotation of the drum may be at will prevented.

The operation and advantages of this in-

vention will be readily understood from the foregoing description taken in connection with the drawings hereto annexed. The articles of food and the like that are to be preserved are placed on the shelves of the receptacle or dumb waiter, and the latter is lowered into the cavity 9 in the ground which may be of any desired depth, and within which the temperature is considerably less than that of the external atmosphere. Proper ventilation is maintained through the air spaces of the casing and the vent tube 11; it being obvious that when the dumb-waiter is lowered into the well or cavity in the ground, a portion of the relatively cold air filling said well or cavity will be displaced and will be forced upward through the apertures 10 into the air spaces 3 between the walls of the casing, the relatively warm air occupying said spaces being ejected through the vent tube 11. In like manner, when the dumb waiter is elevated, the space occupied thereby will be filled with air rushing downward from above. A circulation will thus be established every time the dumb-waiter is raised or lowered, which is effective in promoting a cool and sanitary condition. The air spaces also serve to maintain a minimum temperature within the casing. By means of the windlass the receptacle or dumb waiter may be very conveniently elevated within the casing A when it is desired to have access to the contents thereof; and the dumb waiter may in like manner be restored to a position within the cavity 9.

The general construction is simple and inexpensive, and the improved refrigerating device is thoroughly efficient for the purposes for which it is provided.

Having thus fully described the invention, what is claimed as new is:—

1. In a refrigerating device, a casing supported above and adjacent to a cavity in the ground, said casing comprising outer and inner walls and upper and lower caps arranged

to form intervening air spaces a base supporting the walls and having apertures establishing communication between the air spaces and the cavity in the ground, a vent tube connecting the air spaces with the external atmosphere, guide rails arranged within the casing and extending through the base into the cavity in the ground, a receptacle or dumb waiter arranged for travel upon the rails, and hoisting means for raising and lowering the dumb waiter.

2. In a refrigerating device of the class described, a casing supported above and adjacent to a cavity in the ground, said casing being constructed with interior air spaces and with a non-conducting lining, a base supporting the casing above the cavity and having apertures registering with the air spaces, a vent tube connecting the air spaces with the external atmosphere, a receptacle or dumb waiter supported for vertical movement within the casing and the cavity; and hoisting mechanism for adjusting the receptacle or dumb waiter.

3. In a refrigerating device of the class described, a base or supporting member arranged above and adjacent to a cavity in the ground, a double walled casing supported upon the base, the latter being provided with apertures registering with the air spaces between the walls of the casing and with a large opening connecting the interior of the casing with the cavity in the ground, guide-rails extending from the interior of the casing into the cavity, a dumb waiter guided upon the rails, and means for hoisting and adjusting the dumb waiter; the doubled walled casing being provided with a door affording access to the dumb waiter.

In testimony whereof, I affix my signature in presence of two witnesses.

MICHAEL P. SHEA.
